CASE FOR EAR SURGERY INSTRUMENTS

Robert A. MacKinnon, Boston, Mass., assignor to MacKinnon Instruments Inc., Boston, Mass., a corporation of Massachusetts

Filed Apr. 26, 1962, Ser. No. 69,855

Term of patent 3½ years

(Cl. D87—5)

FIGURE 1 is a perspective view of a case for ear surgery instruments, showing my new design; FIGURE 2 is a front view thereof; FIGURE 3 is a side view thereof; and FIGURE 4 is a top view thereof.

The back of the case is substantially plain and unornamented except for the two hinges shown in FIGURES 3 and 4.

I claim:

The ornamental design for a case for ear surgery instruments, substantially as shown and described.
